UNITED STATES PATENT OFFICE.

CARLO F. Z. CARACRISTI, OF GRANITE, ASSIGNOR OF ONE-HALF TO JULIUS E. ROCKWELL, OF RICHMOND, VIRGINIA.

RAILROAD TIE, CHAIR, AND CLAMP.

SPECIFICATION forming part of Letters Patent No. 416,050, dated November 26, 1889.

Application filed June 25, 1889. Serial No. 315,546. (No model.)

To all whom it may concern:

Be it known that I, CARLO F. Z. CARACRISTI, a citizen of the United States, residing at Granite, in the county of Chesterfield and State of Virginia, have invented certain new and useful Improvements in Railroad Ties, Chairs, and Clamps; and I do hereby declare the following to be a full, clear, and exact description of the invention, such as will enable others skilled in the art to which it appertains to make and use the same.

My invention relates to an improvement in railroad ties, chairs, and clamps; and it consists in the peculiar construction and combination of devices hereinafter described and claimed.

In the accompanying drawings, Figure 1 is a perspective view of my improved tie and clamp. Fig. 2 is a longitudinal vertical sectional view of the same. Fig. 3 is a transverse sectional view of one of the chairs.

The ties A are made of iron, either cast, wrought, or rolled, as may be preferred, and are I-shaped in cross-section and thereby provided with the web B, the upper flange C, and the lower flange D. Formed at the ends of the lower flange D are plates E, which constitute the bottoms of the chairs, and depending from the said plates, near the inner ends 30 thereof and arranged transversely thereon, are flanges F, which bear against the inner sides of stone blocks G, which are arranged at suitable distances apart and employed to support the chairs and ties.

35 Pieces of asphalt cloth H are interposed between the blocks of stone and the plates E to form cushions for the chairs. The outer ends of the plates E project beyond the outer sides of the blocks G and form flanges I.

40 A pair of concavo-convex spring-plates K have their lower edges welded or otherwise secured to the sides of each plate E, said spring-plates having their convex sides turned toward each other, as shown, and welded or 45 otherwise secured on the upper edges of the said pairs of spring-plates are plates L, which constitute the upper sides of the chairs. The ends of the chairs are open, so that air may 50 pass freely through them to keep them dry and retard corrosion. The spring-plates K

permit the rails to play vertically a slight distance when a train passes over them, and thereby render the track sufficiently elastic to cause the train to ride smoothly and without excessive jolting and jerking motion. 55

Tie-braces M are arranged at the outer ends of the chairs and are parallel with the track-rails, the said tie-braces being employed to connect the ties together and prevent them from moving laterally on the stone blocks. 60 The said tie-braces have longitudinal recesses or grooves N in their inner sides to receive the projecting flanges I of the plates E, and bolts O are secured in vertical aligned openings in the said tie-braces and said flanges 65 and serve to securely fasten the tie-braces to the ends of the ties. At the inner sides of the tie-braces are formed depending flanges P, which bear against the outer sides of the stone blocks and serve to assist in seating 70 the chairs or ends of the ties firmly on the said blocks.

In the center of each plate L, which constitutes the top of a chair, is a vertical opening R, having a vertical groove S, which communicates with its outer side, and at a suitable distance beyond each opening R is a countersink or recess T, rectangular in form, in the bottom of which is a nut U. 75

I will now describe my improved clamps, 80 which I employ to secure the rails on the chairs. Each of said chairs comprises a circular plate U, having a pair of arms V, extending obliquely from opposite sides thereof and in opposite directions. The outer ends of 85 said arms are curved outward in opposite directions and provided with turned-up tips or locking-flanges W, adapted to engage the base-flanges of the track-rail X, which latter is of the usual well-known form. Extending 90 outward from the center of each clamp is an arm Y, having an opening Z, adapted to register with the threaded opening in the nut U', and depending from the center of each clamp 95 is a pivot-stud A', adapted to fit in the opening R and having a key or head B', arranged at right angles to the arm Y and adapted to operate in the groove S when placing the clamp on or removing the same from the chair. The said key or head B' passes out 100

of alignment with the said groove and under the plate L when the clamp-plate is turned to such position as to cause the lips W to engage the base-flanges of the rail, and thereby 5 the said key or head serves to secure the clamp-plate against being lifted from the chairs. When the clamp-plate is in this position, its arm Y is over the countersink or recess T, and a bolt C' is then inserted in the 10 opening Z and screwed into the nut and secures the clamp against axial movement, and thus keeps its locking lips or flanges in engagement with the base-flanges of the rail.

Having thus described my invention, I 15 claim—

1. In a railroad, the blocks G, the metallic cross-ties thereon, having the depending flanges bearing against the inner sides thereof, and the tie-braces connecting the outer 20 ends of the ties and having the depending flanges bearing against the outer sides of the blocks, substantially as described.

2. The combination of the ties having flanges at their outer end, the tie-braces 25 having the longitudinal recesses or grooves on their inner sides to receive said flanges, and bolts to secure said braces to the ties, substantially as described.

3. The metallic tie I-shaped in cross-section and having the broadened end extensions or plates E, the pairs of concavo-convex 30

spring-plates K, having their lower edges welded or otherwise secured to the sides of plates E, and the plates L, supported on said spring-plates and adapted to support the 35 rails, substantially as described.

4. The chairs having the openings R, with communicating slots or grooves S, in combination with the clamp-plates having the depending pivot-studs to engage said openings 40 R and heads or keys on said studs to operate in the slots or grooves S, for the purpose set forth, the said clamp-plates having the arms provided with the locking lips or flanges to engage the base-flanges of the rails, substan- 45 tially as described.

5. The combination of the chair having the opening R and communicating groove S with the clamp-plate having the pivot-stud to enter the opening R and the arm Y, the 50 said stud having a head or key out of line with the said arm, and the said clamp-plate being further provided with the oppositely-extending arms having the locking lips or flanges to engage the base-flanges of the rails, 55 substantially as described.

In testimony whereof I affix my signature in presence of two witnesses.

CARLO F. Z. CARACRISTI.
